(57) **CLAIM**

We claim the ornamental design for an inside diameter measurement tool, as shown and described.

DESCRIPTION

FIG. 1 is a front perspective view of an inside diameter measurement tool showing our new design;

FIG. 2 is a front view thereof, the rear view being a mirror image thereof;

FIG. 3 is a left-side view thereof;

FIG. 4 is a right-side view thereof;

FIG. 5 is a top view thereof; and,

FIG. 6 is a bottom view thereof.

The broken lines depict environmental subject matter only and form no part of the claimed design.
